EDWARD LAAS, OF CHICAGO, ILLINOIS, ASSIGNOR, BY MESNE ASSIGNMENTS, TO OTTO R. BARNETT, OF CHICAGO, ILLINOIS.

RAIL-ANCHOR.

1,262,214.

Specification of Letters Patent. Patented Apr. 9, 1918.

Application filed July 17, 1916. Serial No. 109,669.

To all whom it may concern:

Be it known that I, EDWARD LAAS, a citizen of the United States, residing at Chicago, in the county of Cook and State 5 of Illinois, have invented certain new and useful Improvements in Rail-Anchors, of which the following is a specification.

My invention relates to a rail anchor, that is, to a device for preventing the longitudinal creep of a railroad rail, and more particularly to a rail anchor of the type depending for its hold on the rail upon a wedging engagement between the parts of the device. In a device of this character 15 it is essential to maintain a close wedging relationship between the parts. Any looseness destroys the effectiveness of the device. Under conditions created by the passage of trains over the track or by changes of temperature or other causes, forces are brought 20 into play the tendency of which is to loosen the wedging relation between the parts of the device. The vibration of the rail is likely to bring this about. When the rail contracts with a fall in temperature, it may 25 tend to pull one member of the device with it, particularly if the other member is obstructed by the ballast. There is also said to be a counter-creeping movement which 30 takes place in the direction opposite to the traffic after the forward stress on the rails has ceased. In addition to these forces there are the forces developed by the undulating movements of the rail under the 35 stresses of the wheels of the train. All of these forces tend, in one way or another, to loosen one wedge member from the other so that they are a constant menace to the continued effectiveness of an anti-creeping 40 device of the wedge type.

The principal object of my invention is to provide a rail anchor which will be capable of resisting these disturbing influences and which will, therefore, maintain its hold on 45 the rail under all conditions.

The invention has for a further object to provide a rail anchor which will be light in weight, inexpensive to manufacture and which can be easily applied to the rail.

The invention is illustrated, in certain preferred embodiments, in the accompanying drawings wherein—

Figure 1 is a plan view, with parts in section, of a rail anchor embodying one form 55 of the invention.

Fig. 2 is a sectional view on line 2—2 of Fig. 1.

Fig. 3 is a view, in perspective, of the wedge member of the anchor.

Fig. 4 is a similar view of the spring locking key. 60

Fig. 5 is a view similar to Fig. 1 illustrating a modification.

Fig. 6 is a similar view illustrating another modification. 65

Fig. 7 is a plan view of a somewhat different embodiment of the invention.

Fig. 8 is a sectional view on line 8—8 of Fig. 7.

Fig. 9 is a view, in perspective, of the wedge member employed in the anchor shown in the preceding two figures, and 70

Fig. 10 is a similar view of the locking key.

Like characters of reference designate like 75 parts in the several figures of the drawings.

Referring first to Figs. 1 to 4 inclusive, A indicates a railroad rail and B one of the cross ties on which the rail is supported. The anchor consists of a rail embracing 80 member 25, a wedge member 26, and a spring locking key 27. In this embodiment of the invention the rail embracing member is formed with a foot or flange 28 adapted to bear against the face of tie B. This 85 part of the device is referred to as a tie abutting member but it will be understood that the device might be arranged to bear against or be anchored to any stationary part of the roadbed. 90

The rail embracing member is formed at one end with a jaw 29 adapted to engage one edge of the base flange of rail A and at the other end with a larger jaw 30 adapted to receive the wedge 26. The latter is 95 formed with a small recess 31, a larger recess 32 and a connecting groove 33. The spring locking key is formed at one end with a right angle offset 34 adapted to fit into recess 31 of the wedge, and the other 100 end being bent into a substantially spiral curve 35 adapted to enter the recess 32 of the key, the intervening part of the key lying in groove 33 when the device is applied to the rail. The configuration of the key is 105 preferably such that it assumes the position indicated by the dotted lines in Fig. 1 when it is first placed in the wedge, that is, before the wedge is driven into jaw 30. By driving the wedge into jaw 30 the spring key is 110

bent and the curved part 35 is compressed, as indicated by the full lines in Fig. 1. By this arrangement a spring pressure is brought about between the wedge and the rail which absorbs vibration and prevents the wedge from backing out of jaw 30. At the same time, inasmuch as the key will retreat into the recesses formed in the wedge, the wedging relation between the parts of the anchor and the rail is rigid and positive, that is to say, the hold of the device on the rail as against the forward creeping stresses, is not dependent on the strength or stiffness of the spring.

15 It will be apparent that the relationship of the parts might be varied without departure from the principles of the invention, and two such possible modifications are indicated in Figs. 5 and 6.

20 In Fig. 5 the spring key 36 is arranged between the wedge 37 and jaw 38 of the rail embracing member 39, the wedge being suitably recessed on the edge adjacent the inner face of the jaw as indicated at 40.

25 In the arrangement shown in Fig. 6, the jaw 41 of the rail embracing member 42 is formed with recesses 43, 44 and groove 45 to receive the locking key 46 which bears and exerts its spring pressure against the 30 adjacent edge of the wedge 47.

35 A somewhat different embodiment of the invention is shown in Figs. 7 to 10 inclusive. The wedge 48 is formed with a notch or recess 49 to receive the offset 50 formed on the locking key 51, the other extremity of which is bent, as indicated at 52, so that it bears against and bites into the edge of the rail base.

40 In the rail anchor shown in Figs. 1 to 5 inclusive, and 7 to 10 inclusive, the spring locking key is linked to the wedge member so that when the wedge is driven in place the key will follow. Moreover, the key cannot retreat from its operative position so long as 45 the key maintains its hold on the rail or on the yoke member of the anchor. The arrangement of the locking key with an offset which fits into a recess in the key is advantageous because as the offset cannot bend 50 there is little likelihood of its being sheared or broken off when the key is driven into place with the wedge. In Fig. 6 the key forms, in the same way, effectively a part of the yoke member of the anchor.

55 I claim:

1. A rail anchor comprising rail engaging elements having a wedging relation, one of which is provided with a tie abutting member, and a spring locking device which 60 is anchored at one extremity as against movement in either direction to one of said elements, the other extremity of which is provided with a curved engaging surface and free to be strained by application of the 65 anchor to the rail whereby said locking de-

vice maintains the parts of the anchor in proper wedging relation with the rail.

2. A rail anchor comprising rail engaging elements having a wedging relation, one of which is provided with a tie abutting member and one of which is formed with a recess, and a spring locking device provided at one extremity with an offset to fit into said recess, the other extremity of which is curved outwardly and free to be strained by 70 application of the anchor to the rail whereby said locking device maintains the parts of the anchor in proper wedging relation with the rail.

3. A rail anchor comprising rail engaging 80 elements having a wedging relation, one of which is provided with a tie abutting member, and a spring locking device which is anchored at one extremity as against movement in either direction to one of said elements, the other extremity of which has a substantially spiral configuration and is adapted to be contracted by application of the anchor to the rail whereby said locking device maintains the parts of the anchor in 85 proper wedging relation with the rail.

4. A rail anchor comprising rail engaging elements having a wedging relation, one of which is provided with a tie abutting member, and a spring locking device which is anchored at one extremity as against movement in either direction to one of said elements, the other extremity of which is curved and bears with its convex side upon the rail and is free to be strained by application of the anchor to the rail whereby said locking device maintains the parts of the anchor in 90 proper wedging relation with the rail.

5. A rail anchor comprising rail engaging 105 elements having a wedging relation, one of which is provided with a tie abutting member and one of which elements is formed with a recess, and a spring locking device anchored at one end to one of said members and curving outwardly therefrom and adapted to lie in said recess and arranged so as to be strained by application of the anchor to the rail whereby said locking device maintains the parts of the anchor in proper 110 wedging relation with the rail.

6. A rail anchor comprising rail engaging elements having a wedging relation, one of which is provided with a tie abutting member and one of which elements is formed 120 with a recess, and a spring locking device anchored at one end to one of said members, the other end being substantially in the form of a spiral curve and lying in said recess and being arranged so as to be contracted by application of the anchor to the rail.

7. A rail anchor comprising rail engaging elements having a wedging relation, one of which is provided with a tie abutting mem- 130

ber and one of which elements is formed with two recesses and a connecting groove, and a spring locking device formed at one end with an offset adapted to extend into one of said recesses and a curved portion adapted to lie in the other recess, with the intervening part lying in said connecting groove, said device being arranged so as to be strained by application of the anchor to the rail whereby it maintains the parts of the anchor in proper wedging relation with the rail.

8. A rail anchor comprising rail engaging elements having a wedging relation, one of which is provided with a tie abutting member, and one of which elements is formed with two recesses and a connecting groove, and a spring-locking device formed at one end with an offset adapted to extend into one of said recesses, the other end being in the form of a spiral curve adapted to lie in the other recess, said device being arranged so as to be strained by application of the anchor to the rail, whereby it maintains the parts of the anchor in proper wedging relation with the rail.

9. A rail anchor comprising a rail embracing member formed with a tie abutting foot, a wedge member which intervenes between the base flange of the rail and one end of the rail embracing member, and a spring-locking device which is anchored at one extremity, as against movement in either direction, to one of said members, the other extremity of which is provided with a smooth engaging surface and is free to be strained by application of the anchor to the rail, whereby said locking device maintains the parts of the anchor in proper wedging relation with the rail.

10. A rail anchor comprising a rail embracing member formed with a tie abutting foot, a wedge member which intervenes between the base flange of the rail and one end of the rail embracing member, one of said members being formed with a recess, and a spring-locking device provided at one extremity with an offset to fit into said recess and being curved to present a convex surface directed outwardly from said recess and free to be strained by application of the anchor to the rail, whereby said locking device maintains the parts of the anchor in proper wedging relation with the rail.

11. A rail anchor comprising a rail embracing member formed with a tie abutting foot, a wedge member which intervenes between the base flange of the rail and one end of the rail embracing member, and a spring-locking device which is anchored at one extremity, as against movement in either direction, to one of said members, the other extremity of which has a substantially spiral configuration and is adapted to be contracted by application of the anchor to the

rail, whereby said device maintains the parts of the anchor in proper wedging relation with the rail.

12. A rail anchor comprising a rail embracing member formed with a tie abutting foot, a wedge member which intervenes between the base flange of the rail and one end of the rail embracing member, and a spring-locking device which is anchored at one extremity, as against movement in either direction, to one of said members, the other extremity of which is curved and bears with its curved side upon the rail and is free to be strained by application of the anchor to the rail, whereby said locking device maintains the parts of the anchor in proper wedging relation with the rail.

13. A rail anchor comprising a rail embracing member formed with a tie abutting foot, a wedge member which intervenes between the base flange of the rail and one end of the rail embracing member, one of said members being formed with a recess, and a spring-locking device anchored at one end to said member, the other end being curved and adapted to lie in said recess with its convex side outward and arranged so as to be strained by application of the anchor to the rail, whereby said locking device maintains the parts of the anchor in proper wedging relation with the rail.

14. A rail anchor comprising a rail embracing member formed with a tie abutting foot, a wedge member which intervenes between the base flange of the rail and one end of the rail embracing member, one of said members being formed with a recess, and a spring-locking device anchored at one end to said member, the other end being substantially in the form of a spiral curve and lying in said recess and being arranged so as to be contracted by application of the anchor to the rail.

15. A rail anchor comprising a rail embracing member formed with a tie abutting foot, a wedge member which intervenes between the base flange of the rail and one end of the rail embracing member, one of said members being formed with two recesses and a connecting groove, and a spiral locking device formed at one end with an offset adapted to extend into one of said recesses, and a curved portion adapted to lie in the other recess with the intervening part lying in said connecting groove, said device being arranged so as to be strained by application of the anchor to the rail, whereby it maintains the parts of the anchor in proper wedging relation with the rail.

16. A rail anchor comprising a rail embracing member formed with a tie abutting foot, a wedge member which intervenes between the base flange of the rail and one end of the rail embracing member, one of said members being formed with two recesses and

a connecting groove, and a spiral locking device formed at one end with an offset adapted to extend into one of said recesses, the other end being in the form of a spiral curve adapted to lie in the other recess, said device being arranged so as to be strained by application of the anchor to the rail, whereby it maintains the parts of the anchor in proper wedging relation with the 10 rail.

17. A rail anchor comprising a rail embracing member formed with a tie abutting foot, a wedge member which intervenes be-

tween the base flange of the rail and one end of the rail embracing member, the wedge being formed in one edge with two recesses and a connecting groove, and a spring-locking device having an offset adapted to extend into one of said recesses and a curved portion at the other end thereof adapted to lie in the other recess, the intervening portion extending through said connecting groove whereby said device is put under bending strain when the anchor is applied to a rail. 15 20

EDWARD LAAS.
